US00D606659S

(12) **United States Design Patent**
Kiani et al.

(10) **Patent No.:** **US D606,659 S**
(45) **Date of Patent:** **** Dec. 22, 2009**

(54) **PATIENT MONITOR**

(75) Inventors: **Massi Joe E. Kiani**, Laguna Niguel, CA (US); **Marcelo Lamego**, Rancho Santa Margarita, CA (US); **Sean Merritt**, Lake Forest, CA (US); **Cristiano Dalvi**, Mission Viejo, CA (US); **Hung Vo**, Garden Grove, CA (US); **Johannes Bruinsma**, Mission Viejo, CA (US); **Jeroen Poeze**, Mission Viejo, CA (US); **Ferdyan Lesmana**, Irvine, CA (US); **Greg Olsen**, Trabuco Canyon, CA (US)

(73) Assignee: **Masimo Laboratories, Inc.**, Irvine, CA (US)

(**) Term: **14 Years**

(21) Appl. No.: **29/323,408**

(22) Filed: **Aug. 25, 2008**

(51) LOC (9) Cl. **24-01**

(52) U.S. Cl. **D24/186**

(58) Field of Classification Search D24/107, D24/137, 138, 158, 160, 164, 165, 167, 170, D24/186-187, 231; 600/300, 301, 368, 372, 600/481, 529, 544, 546, 554, 561; D10/78, D10/81, 104; D14/225, 226, 137, 424, 446; 128/903, 671

CLAIM

The ornamental design for patient monitor, as shown and described.

DESCRIPTION

FIG. 1 is a perspective view of a PATIENT MONITOR showing our new design;

FIG. 2 is front view thereof;

FIG. 3 is a back view thereof;

FIG. 4 is a top view thereof;

FIG. 5 is a bottom view thereof; and,

FIG. 6 is a right side view, with the left side view being a mirror image thereof.

Where utilized, phantom lining is for illustrative purposes only and is not intended to limit or form any part of the claimed design.

The broken lines are included for the purpose of illustrating portions of the patient monitor that forms no part of the claimed design.

1 Claim, 5 Drawing Sheets
